UNITED STATES PATENT OFFICE.

JOHN BOYD, OF GLASGOW, SCOTLAND.

STOP-MOTION MECHANISM FOR WINDING AND TWISTING MACHINES, &c.

SPECIFICATION forming part of Letters Patent No. 244,538, dated July 19, 1881.

Application filed November 30, 1880. (No model.) Patented in England July 21, 1879.

To all whom it may concern:

Be it known that I, JOHN BOYD, a subject of the Queen of Great Britain and Ireland, residing in Glasgow, Scotland, have invented certain Improvements in Stop-Motion Mechanism for Winding and Twisting Machines, &c., (patented in England July 21, A. D. 1879, No. 2,953,) of which the following is a specification.

My invention relates to stop-motions for twisting and winding machines and other machines of analogous character; and the main feature of my invention consists in so constructing the machine that the tube or spindle carrying the bobbin is made to control a stop-motion trigger, another prominent feature of my invention consisting of mechanism, described hereinafter, for elevating the upper feed-roller above the driven rollers, and for seizing the threads in obedience to the action of a trigger or triggers on the breakage or failure of one or more of the threads.

Other features of my invention are too fully explained hereinafter to need preliminary description.

Figure 1, Sheet 1, is a vertical section of sufficient of a winding and twisting machine to give a general view of my improvements; Figs. 2 and 3, Sheet 2, an enlarged vertical section of part of Fig. 1, showing some of the operating parts in different positions; Fig. 4, Sheet 3, a perspective view of Fig. 3; Fig. 5, a detached view of part of Fig. 3; Fig. 6, a detached view of part of Figs. 2 and 3, and Fig. 7 a view of a modification.

The end frames, A, of the machine are connected together by longitudinal rails B, B', B², and B³, as in other machines of the class to which my invention relates, C being one of the winding-spindles driven from a pulley or drum, F, on the driving-shaft G by a band, D, which passes round a grooved pulley on the said spindle, the latter being provided with an ordinary flier, a, for twisting the yarn and directing it to the bobbin c, which rests on the lifting-rail b. There are in the present instance four threads to be twisted and wound, these threads being derived from as many bobbins, which are shown most clearly in Figs. 2 and 3. Each bobbin H fits snugly, but so as to turn freely, on a tube, h, Fig. 2, and rests on a carrier, I, into which the tube is tightly fitted, both tube and carrier

being supported by a fixed spindle, J, the apex of which is adapted to a recess in a filling-piece fitted into the upper portion of the tube, the fixed spindle being carried by a bracket, K, on the under side of a board, L, secured to the rail B' of the machine. From each carrier I, beneath the board L, projects a short arm, f, connected by a cord, f', to an arm, h', of the trigger M, which will be more particularly referred to hereinafter. The weight of the arm i of the said trigger is slightly in excess of that of the arm j, which is provided with an adjustable counter-balance for insuring this preponderance of the arm i. From the carrier above the board L projects an arm or crank, k, having a vertical pin, k', against which the thread bears, the tension on the thread being so exerted on the arm that it tends to turn the carrier and to maintain the trigger in the position shown in Fig. 2. The perspective view, Fig. 6, illustrates the manner of limiting the movement of the carrier by stops on the bracket.

In machines in which the bobbins turn at a high speed, or where there is friction enough of the bobbin on the carrier, the crank-pins may be dispensed with and the cord simply coiled round the tube or a spindle adapted to bearings.

The threads from the four bobbins pass through an eye, g, thence over the feed-rollers N N' and beneath the upper feed-roller, P, to the flier, by which they are twisted and wound round the bobbin c.

The feed-rollers N N' have journals adapted to bearings on the frame, as usual, and are driven from the shaft G through the medium of appropriate gearing, as indicated by dotted lines in Fig. 1, and hereinafter referred to.

The upper roller, P, (best observed in Fig. 5,) is supported by the rollers N N', and by its weight presses the four threads against these rollers as long as all the four threads remain unbroken; but when any one or more of these threads is broken or fails a rod, Q, owing to mechanism explained hereinafter, will instantly rise and elevate the roller P, which will be supported by a concave plate, m, on the upper end of the rod, all the threads being then grasped and confined between the plate and the roller.

Referring to Fig. 5, it will be noticed that

a grooved journal, p' , projects from one end of the roller P , and that a slotted plate, m' , secured to the rod Q , is adapted to the groove of this journal, the object of this plate being 5 to maintain the roller P in its proper position. The vertical rod Q passes through and is guided by the rail B of the frame, and is connected at its lower end to a lever, R , which is pivoted to a bracket, n , secured to the rail B^2 , this 10 lever being so weighted that, under the circumstances explained hereinafter it will raise the rod Q and perform the functions described above.

It will be understood that there is a trigger, 15 M , for each thread, and hence that there are in the present instance four triggers for one set of four bobbins. The four triggers are pivoted independently of each other to a spring-bolt, S , which passes through and is guided by 20 the rail B of the frame, the peculiar construction of which will be best understood by reference to the perspective view, Fig. 4, Sheet 3. A bent arm, p , projects from the rear of the bolt S , and carries a plate, q , having upwardly-projecting lugs t , which, with the arm p , form four recesses, and in each recess is pivoted a trigger by a pin common to all four of the triggers. The movement of the triggers is limited 25 in the direction of the arrow, Fig. 4, by a rod, u , and in the opposite direction by the rail B , Fig. 2. A spring, V , contained within a slot in the bolt and confined between one end of the slot and a plate bearing against a flange of the rail B , tends to force the said bolt in the 30 direction of the arrow, and part of this bolt is reduced in thickness, so as to form an inclined shoulder, x , faced with a steel plate, the reduced portion of the bolt passing through a slot, y , Fig. 5, in the vertical bar Q , the rear of 35 this bar having also a steel plate, the upper edge of which is flush with the bottom of the slot. As long as all the threads continue to unwind from the bobbins, the carriers, by the tension of their threads caused by the friction 40 of the bobbin, will be turned round on their spindles or pivots, and all the triggers will be in the position shown in Fig. 2, the upper feed-roller will be supported solely by the rollers N and N' , and the rod Q will be retained in its de- 45 pressed condition, owing to the bearing of its steel plate against the under edge of the steel plate on the shoulder x of the bolt S , and the drawing of all four threads through the feed-rollers will continue. The moment one of the 50 threads breaks or fails its bobbin and carrier and trigger, owing to the preponderance of its arm i , will automatically cause the unwinding of the cord on the carrier, and will assume the positions shown in Fig. 3, and the end of the 55 arm will be within range of cam-like projections T' on a shaft, T , which has its bearings on the frame, and which is driven in the direction of the arrow from the driving-shaft through the medium of suitable gearing.

60 65 As indicated by dotted lines in Fig. 1, a belt passing over a pulley on the shaft G drives a shaft carrying a cog-wheel gearing into a wheel

on the shaft T . The latter imparts motion to the back feed-roller, N' , through a pinion on the shaft gearing into a pinion on the roller. The 70 roller N is driven from the roller N' through the medium of an intermediate pinion. (Shown by dotted lines.)

When one of the projections on the shaft strikes the arm i of the trigger the bolt will 75 be pushed back, the rod Q will be released from the control of the bolt, and, influenced by the weighted lever R , will rise and elevate the upper feed-roller, P , as described above. The feeding will consequently be discontinued, 80 and all the threads, including that which was broken, between its bobbin and feed-rollers, will be confined between the said roller P and the plate on the top of the rods. When the rod Q rises its steel plate, acting on the inclined steel plate of the bolt, will push the latter back farther than it was pushed by the projection on the shaft T' , so that the trigger will be entirely beyond range of the projections until the rod Q is depressed. 90

When it is desired to stop the machine by hand this may be readily done by simply pressing on the projecting end w of the spring-bolt S so as to release the rod Q .

After a broken thread has been pieced and 95 the bobbin has been turned until the tension on the thread lifts the trigger, the roller P and rod Q may be depressed until the former bears on the other rollers and the end of the bolt, owing to its spring, assumes its former position, Fig. 2.

Instead of mounting each bobbin H on a tube attached to a carrier, the bobbin may be mounted directly on a spindle, h^2 , adapted to bearings in the frame, and having the cord f' , 105 which is connected to the trigger, wound on the spindle by the tension or friction of the yarns or threads, as illustrated in the modification, Fig. 7.

Instead of causing the friction of the bobbin on the tube or spindle to control the stop-motion trigger through the medium of a cord, f' , other mechanical devices—such as a lever or cam—may be employed. Any of the ordinary braking appliances may be combined 110 with the rod Q and intervening actuating mechanism for this purpose. I may state, however, that I prefer as a means of stopping the spindle a device which forms the subject of a separate application for a patent filed by 115 me November 30, 1880, serial No. 21,368, and which may be briefly described as follows: When the rod Q rises the cord D , which drives the spindle, is slack, and this cord is gripped between a jaw on the lower end of the 120 rod Q and a fixed jaw, so that the motion of the spindle must be arrested; but when the rod Q is depressed a pulley on the lever R will 125 tighten the cord, which will at the same time be released from the jaws.

I do not desire to claim, broadly, in this application the combination of the cam-shaft, stop-motion trigger, and spring-bolt with a rod or lever which is adapted to be supported by 130

the said bolt, and which, when released, pushes the trigger back out of the way of the rotating cam-shaft, as this combination forms the subject of a separate application filed by me April 30, 1880, serial No. 8,753; nor do I desire to claim in this application the special means shown for counterbalancing the trigger, as this forms the subject of a separate application filed by myself and T. A. Boyd, May 10, 1880, serial No. 9,180.

I claim as my invention—

1. The combination of winding mechanism, spindle, and carrier with a stop-motion trigger connected to or operating in connection therewith, said carrier having a crank-pin for the thread to bear against, substantially as specified.

2. The combination of winding mechanism and carrier or spindle on which the bobbin is fitted with a stop-motion trigger having an arm connected by a cord to the said carrier or spindle, all substantially as set forth.

3. The combination of the fixed spindle J, the carrier I, the tube h, fitted and secured to the carrier and supported by the spindle, substantially as described.

4. The combination of the bracket K and spindle with the carrier I and stops on the bracket for limiting the movement of the carrier.

5. The combination of the rollers N N' and

driving mechanism, the roller P, and a rod, Q, carrying said roller P, and devices for imparting an upward tendency to said rod with a stop-motion trigger, and a spring-bolt for retaining and releasing the rod in obedience to the action of said trigger.

6. The combination of rollers N N' and rod Q, having a plate, m, with the roller P, carried by said rod, substantially as described, whereby on the raising of the said rod the roller P will rest on said plate m.

7. The combination of the rollers N N' and movable rod Q, having a plate, m, and slotted plate m', with the roller P, having a grooved journal adapted to said slotted plate, as set forth.

8. The combination of the frame, rollers N N', and driving mechanism, the roller P, and rod Q, carrying said roller P, and devices for imparting an upward tendency to said rod, with a spring-bolt for retaining the rod, and having an end, w, projecting beyond the frame-rail, as and for the purpose set forth.

In testimony whereof I have signed my name to this specification in the presence of two subscribing witnesses.

JOHN BOYD.
